UNITED STATES PATENT OFFICE.

JOHN H. RIGBY, OF BEVERLY, MASSACHUSETTS, ASSIGNOR TO UNITED SHOE MACHINERY COMPANY, OF PATERSON, NEW JERSEY, A CORPORATION OF NEW JERSEY.

HEEL-BUILDING MACHINE.

1,249,502.

Specification of Letters Patent. Patented Dec. 11, 1917.

Application filed March 27, 1914. Serial No. 827,608.

To all whom it may concern:

Be it known that I, JOHN H. RIGBY, a citizen of the United States, residing at Beverly, in the county of Essex and State 5 of Massachusetts, have invented certain Improvements in Heel-Building Machines, of which the following description, in connection with the accompanying drawings, is a specification, like reference characters on 10 the drawings indicating like parts in the several figures.

This invention relates to heel building machines, and is of special utility when embodied in that type of machine in which heel 15 lifts are assembled in a mold for nailing and there held by a presser mounted to swing into position for operation by a member actuated by power through the medium preferably of a power shaft provided with a Horton 20 clutch, including the usual roller cage and tripping arm, such a machine forming the subject of Letters Patent No. 1,148,716, granted Aug. 3, 1915. Certain features of the invention, however, are not limited in 25 their utility to use in connection with a machine of the particular kind referred to, but may be embodied in many different machines for operating upon shoes.

An important object of this invention is to 30 obviate the possibility, with a machine of this character, of permitting the presser to be actuated by the power actuated member, with resulting disaster to the machine, when the presser occupies a rearward position, not 35 in proper alinement with the mold.

Such a contingency may arise, because the Horton clutch is tripped by swinging the presser arm forward, and if this be done when the power is turned off, as may occur 40 by accident or design during the lunch hour, for example, it is possible, with the form of starting mechanism heretofore in use, to swing back the presser arm without throwing off the clutch, and accordingly, when the 45 power is turned on, the presser is automatically actuated by the clutch, and not being over the mold, the presser engages other parts of the machine destructively.

In accordance with this invention, therefore, means are provided for preventing the power devices, in such a machine, from actuating the presser member when it has been

swung back from normal pressing position (over the mold), and preferably this is accomplished by providing connective means, such as a link, pivotally mounted on the swinging presser-operating member, and constructed and arranged to be engaged with the roller cage of the Horton clutch, acting upon the latter to rotate it backward and throw off the clutch whenever the presser-operating member is swung back from normal pressing position. 65 60

In the following specification one mechanical embodiment of the invention will be 65 specifically described for the purpose of illustration, but it should be understood that the invention is not limited in its scope to the embodiment described in detail, except in so far as defined by the claims at the end 70 of said specification.

The various features of my invention will be illustrated in the accompanying drawing and described fully in the specification and pointed out in the claims. 75

In the drawing, the figure shows in side elevation a machine in the construction of which my improvements have been embodied, parts being broken away to reveal interior construction. 80

In its general features the machine illustrated embodies (with some differences in design), the devices forming the subject of the aforesaid patent, to which reference may be had for a more detailed explanation. 85

The frame of the machine is designated by the reference numeral 10 and may be of any suitable shape and construction. Pivotally mounted within the frame 10 is a swinging arm 12 which is constructed to 90 swing about the pivot pin 14 mounted on a lever 15 which is depressed, after the starting of the machine, by a cam 132 upon the main drive shaft 128, thus applying pressure to the heel presser 72, provided that 95 the latter has been swung forward from the position illustrated, in which position, however, my invention provides that power can not be applied to depress arm 12 and presser 72, which would destroy the parts at the 100 rear of the heel mold 18.

The operation of cam 132 by shaft 128 is controlled by any suitable mechanism, and as one convenient form of such mechanism

I have shown a Horton clutch comprising the usual roller cage 110 and co-operating spring trigger arm 106, which occupies in the drawing its position to prevent operation 5 of the clutch, the latter being thrown off by a device to be described.

To permit operation of the clutch, any suitable mechanism may be utilized, and I have shown, by way of example, a link 100, 10 mounted pivotally at 101 on arm 12, and having a notch shoulder at 103 to be engaged with a pin 105 on an arm 107 fast on the rock shaft 109 which carries the clutch trigger 106, and to trip the clutch it is only 15 necessary to pull forward the presser 72 and arm 12 to their normal operative position, with presser 72 above mold 18, when link 100 will drag over the lever 107 and rock the shaft 109 to pull the trigger 106 and release the roller cage 110, which will then cause the clutch to engage and the shaft 128 will rotate cam 132 to depress lever 15 and operate arm 12 and presser 72.

In accordance with my invention, to obviate destructive action by operation of the presser 72 when arm 12 is in the position illustrated, I have provided link 100 with a part 200 constructed and arranged to engage a suitable portion of the roller cage 110 of 25 the clutch, such as the pin 201 set in the lump of the cage collar, extending parallel to the axis of shaft 128 and lying in the path of the link 100, which preferably is provided with a projection 202 to engage pin 201 and rotate the roller cage 110 backward 30 to throw out the clutch when the link 100 is moved toward the left by backward swinging of arm 12.

Thus the swinging of presser 72 back 40 from its normal operative position to the illustrated position is always accompanied by throwing out the clutch, rendering the machine inoperative, while it is only necessary to pull forward arm 12 with presser 45 72 to cause operation of the presser, as the link 100 always trips the clutch, acting through levers 107 and 106, when the link is dragged toward the right by swinging movement of arm 12 from the position illustrated. 50

The part 200 may, and preferably will, be mounted adjustably on link 100 and provided with a clamping bolt 204, and springs 205 and 206 may be provided to hold link 55 100 and trigger 106 to their work.

Having thus described my invention, what I claim as new and desire to secure by Letters Patent of the United States is:

1. In a machine of the class described, the 60 combination, with a work support and power means, movable to and from operative position with respect to the work, for exerting pressure upon the work, of a clutch, means to trip the clutch to permit actuation 65 of the pressure exerting means, and means

for throwing off the clutch whenever said power means is moved out of operative position with respect to the work.

2. In a machine of the class described, the combination with means for exerting pressure upon the work, said means comprising a presser mounted to swing into position to operate upon said work, and power devices to actuate said presser, including a clutch, of means to trip said clutch to permit actuation 70 of said presser by power devices when said presser is swung into its normal operating position, and means to throw off said clutch when said presser is swung back from said operating position. 75

3. In a machine of the class described, the combination with means for exerting pressure upon the work, said means comprising a presser member mounted to swing into position to operate said presser upon the work, of a power shaft having a clutch including a rotatable clutch collar to control the actuation of said member by said shaft, and connective means intermediate said member and clutch collar to throw off said 80 collar when said presser occupies its inoperative position relatively to said work. 90

4. In a machine of the class described, the combination with a work-support, of means for exerting pressure upon the work, 95 said means comprising a presser member mounted to swing into normal position to operate said presser, and a power shaft having a clutch including a rotatable clutch collar to control the actuation of said member by said shaft, and connective means intermediate said member and clutch collar to throw off said collar when said presser occupies its inoperative position relative to said work-support, and means to trip said clutch 100 for actuation of said presser when in its normal operating position, relatively to said work-support. 105

5. In a machine of the class described, the combination with a work-support, a 110 presser and a swinging arm constituting a presser-operating means, of a power shaft, a Horton clutch with roller cage and trigger, and a drag-link secured to said arm and extending past said roller cage, said link having means to be engaged with parts connected with said roller cage and trigger respectively, to operate said trigger to trip said clutch to permit actuation of said presser by said power-shaft when said arm is swung to bring said presser into normal operative position, and to reverse said roller cage, to throw off said clutch and prevent power actuation of said presser when said arm is swung away from said work-support. 115

6. In a machine of the class described, a work-support, a swinging and plunging arm provided with a presser, power devices to actuate said arm plungingly to operate 120

said presser, and means, operated by swinging said arm, to permit power-actuation of said presser when in normal operative position relatively to said work-support, and to prevent its operation otherwise.

7. In a machine of the class described, the combination with a work-support, a device to operate upon a shoe-part carried by said support, and power mechanism to actuate said operating device, of a Horton clutch including a roller-cage and trigger

to trip said clutch normally, and a reversing device to throw off said roller-cage when said mechanisms occupy predetermined positions relatively to each other. 15

In testimony whereof I have signed my name to this specification in the presence of two subscribing witnesses.

JOHN H. RIGBY.
